UNITED STATES PATENT OFFICE.

JOHN WALLACE PAGE AND CHARLES M. LAMB, OF ADRIAN, MICHIGAN.

WIRE-FENCE MACHINE.

SPECIFICATION forming part of Letters Patent No. 414,844, dated November 12, 1889.

Application filed August 16, 1889. Serial No. 321,013. (No model.)

To all whom it may concern:

Be it known that we, JOHN WALLACE PAGE and CHARLES M. LAMB, citizens of the United States, residing at Adrian, in the county of 5 Lenawee and State of Michigan, have invented a new and useful Improvement in Wire-Fence Machines, of which the following is a specification.

Our invention relates to a machine for 10 manufacturing wire fence of the construction involving wires to extend horizontally when the fence is in use, and the number of which and their distances apart determine the height of the fence, and vertical or stay wires at de- 15 sired distances apart, which are wound around, and thus fastened to the horizontal wires where they cross the latter; and our machine is especially adapted (though we do not wish to be understood as confining it to such opera- 20 tion) to the manufacture of the kind of fence referred to, having the wires which extend horizontally with the fencing put up bent to resemble a stretched-out coil, in order more especially to adapt it for pasture-fencing, in 25 which application the sinuous appearance afforded it renders it the more readily visible to the animals confined by the fencing, and its construction producing that appearance lends to it a springy quality, whereby it is 30 uninjured by the effect upon it of the temperature to which it is exposed in use, or of the strain of animals running against it.

The operation of our machine, taken as an 35 entirety, is in the nature of a weaving operation, the wires referred to as constituting the horizontal fence-wires affording the warp in the weaving and those referred to as the vertical or stay wires affording the woof.

Following is a description setting forth the 40 general plan of operation of the machine, and briefly explaining our invention in its broadest sense. The warp-wires are fed from spools in desired number and at required distances apart to the take-up mechanism, 45 which receives the finished article and is actuated intermittently to take up lengths thereof, and alternates with a woof-wire winding and stringing device which, as soon as a finished length of the fencing has been taken 50 up, is actuated to travel transversely across the warp-wires, stopping at each and wind-

ing around it a woof-wire, with which it is threaded. Where our invention is applied to the sinuous construction of the fencing for which the mechanism hereinafter described 55 in detail is especially adapted, and which is the article in the manufacture of which we employ it, each of the warp-wires is first coiled throughout a desired short portion of its length and the woof-winding and stringing 60 device then actuated to wind the woof-wire around each warp-wire, and in doing so to string it across the warp-wires just in advance of the termination of each coil. When the woof-wire has been thus applied, the coilers 65 are relieved of the warp-wires, (producing slack in the latter, which may be taken up by an automacally - operating tension device,) when a feeding attachment is actuated, at the end of the operation of uncoiling, to pay 70 from the supply-spools and feed toward the coilers a predetermined length of warp and allow a take-up, which co-operates with and is controlled by the feed, to wind upon itself a length of the finished article. 75

Our machine is illustrated in all its details in the accompanying drawings, in which—

Figure 1 is a partly broken view, in side elevation, of the entire machine; Fig. 2, a longitudinal sectional view of the same; Fig. 80 3, a partly sectional plan view; Fig. 4, a broken view showing the mechanism at the front of the machine for releasing the rack which actuates the coilers and the means operated by movement of the rack to actuate the feed- 85 drum; Fig. 5, a broken detail view in section, taken on the line 5 of Fig. 1, viewed in the direction of the arrows, and showing the stop mechanism for the feed-drum and means for withdrawing the stop to permit rota- 90 tion of the feed-drum; Fig. 6, a similar view taken on the line 6 of Fig. 7, viewed in the direction of the arrow, and showing the clutch- actuating means to produce and release the engagement of the feed-drum with the driv- 95 ing-gear; Fig. 7, a similar view taken on the line 7 of Fig. 6, viewed in the direction of the arrow, and showing in plan the mechanism illustrated in Fig. 6; Fig. 8, a broken per- 100 spective view showing the feed-drum-clutch mechanism; Fig. 9, a broken view in section, taken on the line 9 of Fig. 3, viewed in the

- direction of the arrow and illustrating a coiler, with its pinion engaging with the rack; Fig. 10, a broken sectional view showing the longitudinally-reciprocating rack and partly by dotted lines its stop and releasing mechanism; Fig. 11, a broken view of the machine, showing details of construction and regarded from the side opposite that from which the view illustrated in Fig. 1 is taken; Fig. 12, a broken view showing details illustrated in side elevation at the front end of Fig. 11; Fig. 13, a broken section taken on the line 13 of Fig. 11, viewed in the direction of the arrow and showing toggle-lever mechanism for throwing in and out the clutch (on the side of the machine opposite that presented in Fig. 11) controlling the pinion-shaft from which are actuated the segmental pivotal racks for turning, when released, the take-up drum; Fig. 14, a broken section taken on the line 14 of Fig. 1, viewed in the direction of the arrow and showing details for supporting and dismembering the take-up drum; Fig. 15, a broken perspective view showing a clamp-button detail for holding the warp-wire against slipping on the feed-drum; Fig. 16, a sectional view showing the "needle" or woof-wire winding and stringing device in side elevation; Fig. 17, a similar view of the same, showing the opposite side, taken on the line 17 of Fig. 20 and viewed in the direction of the arrow; Fig. 18, a broken longitudinal section of the same, taken on the line 18 of Fig. 20 and viewed in the direction of the arrow; Fig. 19, a section taken on the line 19 19 of Fig. 16 and viewed in the direction of the arrows; Fig. 20, a section taken on the line 20 of Fig. 18, viewed in the direction of the arrow, and showing the shaft in elevation; Fig. 21, a broken view in longitudinal section showing details of the needle device. Figs. 22, 23, 24, and 25 are perspective views showing various details. Fig. 26 is a section taken at the line 26 26 of Fig. 3, viewed in the direction of the arrows, and showing the endless driving-belt for and the manner of its connection with the needle device; Fig. 27, a section taken on the line 27 of Fig. 17, enlarged and viewed in the direction of the arrow; Fig. 28, a similar view taken on the line 28 of Fig. 27 and viewed in the direction of the arrow; Fig. 29, a diagrammatic view showing the end of the rotary needle threaded with a coil of the woof-wire; Fig. 30, three views illustrating different stages of the formation of the tie by the winding of the woof-wire; Fig. 31, a broken view in rear elevation of the slotted track for the needle device and spring-gate, the spring-finger of the needle device for actuating the gate being indicated by dotted lines; Fig. 32, a similar view of the same, showing the gate-slots as coinciding with the slots in the track; Fig. 33, a section in perspective of the mechanism illustrated in Figs. 31 and 32; Fig. 34, a perspective view of a wire-tension detail; Fig. 35, a broken perspective view of a pivotal dog and other de-
- tails; Fig. 36, a view of a clutch detail, and Fig. 37 a broken view of the fencing manufactured by the machine.
- A is the frame of the machine, which may be rectangular in form, as shown, and of any suitable construction adapting it to support the various parts.
- B, Figs. 2, 3, 9, and 10, is a rack supported to permit it to be reciprocated longitudinally across the front end of the machine on pinions w , journaled to extend at intervals across the rack, which is confined in a suitable guide built at the front of the machine to receive it, one of the pinions having a stem x on which to adjust a winch w' .
- Near the right-hand end of the front of the machine, (being the extreme right side in Fig. 3,) in the path of the reciprocating rack B, is a crank-finger v on an oscillatory rod v' , Figs. 3 and 11, supported on the frame to extend horizontally part way along the right-hand side of the machine, (that is, along the top of Fig. 3,) and carrying near its rear end a crank-finger v^2 , Fig. 13, controlled by a spring x' , and v^3 is a bracket on the frame A, supporting the forward end of a rock-shaft v^4 , which carries at that end a crank-finger v^5 , having its free end bearing against the outer side of the crank-finger v^2 . The rock-shaft has a bearing for its opposite end on a post x^2 of the frame A, beyond the rear side of which post it extends and carries in front of such post a crank-finger v^6 , extending at an acute angle with relation to the finger v^5 , and having pivotally connected with its free end a link v^7 . An arm u is pivotally supported at the upper part of the frame near the rear of the machine (left-hand side of Fig. 3) in a manner to permit it to be moved laterally on its pivot, and extends obliquely forward and downward across the link v^7 , with the free end of which it is pivotally connected at an ear v^8 , the lower end of the arm u being yieldingly controlled against laterally-outward movement on its pivot by means of a spring v^9 . The rock-shaft v^4 carries at its rear end a crank-finger t , connected by a link-rod t' with one end of a lever s , Fig. 11, fulcrumed near its center, to be moved in a vertical plane to the side of the frame A, the opposite end of the lever being linked to a crank-finger r' on the outer end of a rock-shaft r , supported in and extending transversely of the machine through the rearmost right-hand post of the frame and carrying on its inner end an eccentric finger r^2 .
- From the foregoing description of the parts thus far explained it will be seen that when by turning the winch w' the pinion w on its stem x moves the rack B against the crank-finger v the latter is turned outward, thereby rocking the shaft v' and crank-finger v^2 outward, or toward the right, and the crank-finger v^5 on the rock-shaft v^4 in the same direction, whereby the toggle-joint afforded by the crank-finger v^6 and link v^7 is straightened and forces the lower end of the arm u out-

ward against the resistance of the spring u' , causing the crank-finger t to pull the inner end of the lever s downward, and thus effect turning of the rock-shaft r , to advance the finger r^2 inward to the position illustrated by the dotted lines x^3 , Fig. 11, and also to effect other purposes, all as hereinafter set forth. It is to be noted that when the finger r^2 is thus moved inward the racks D and D' , herein-
10 after described, are down at the positions to which they have been permitted to fall in performing their function of actuating the take-up for the finished product.

C, Figs. 1, 2, 3, and 14, is a drum constituting the "take-up" of the machine and comprising two heads q and q' , each formed of a disk having cogs around its periphery and provided on its inner side with radially-disposed angular sockets q^2 , the heads being respectively supported on journals y and y' , extending from their centers and having their bearings in the rearmost posts of the frame A and being connected between the said posts by bars q^4 , the ends of which extend into the sockets q^2 on the opposite heads. The journal y for the head q is threaded, as shown in Fig. 14, where it passes through a stationary nut q^3 , coincident with its journal-bearing, and is provided with a handle q^5 on its outer projecting end, at which to turn it and advance the head q toward or retract it from the head q' to clamp the bars q^4 between the heads or release them from the latter for a purpose hereinafter described, and the handle q^5 should be normally held, as shown, to prevent turning of the take-up C at a wrong time.

On each shaft y and y' between its journal-bearing and the adjacent head is pivotally supported or hung and secured against lateral movement a large segmental rack, that located near the right-hand side of the machine (regarded from the front) being denoted by D' and that near the opposite side by D , and the rack D' carries on its spokes or frame a curved bar z , on which is provided a stud z' , extending into a position where it will strike the eccentric finger r^2 in the movements of the segmental rack. On the inner side of each segmental rack D and D' are provided dogs z^2 , Fig. 2, to engage with the cogs on the heads q and q' and turn the latter, and through them the take-up C, when the segmental racks are caused to fall forward, as hereinafter explained, and stationary dogs z^3 are provided to prevent backward turning of the heads.

A counter-shaft E is suitably supported in the frame of the machine and carries coincident with the segmental racks D and D' pinions D^2 , secured on the counter-shaft to rotate with it, and on the end of the shaft which projects beyond the left-hand side of the machine (or bottom of Fig. 3) is a cog-wheel F, having spokes, as shown in Fig. 1. Beyond the wheel F is secured to the end of its shaft a spring-clutch F' of any suitable construction for its purpose, hereinafter described,

but preferably of the construction illustrated in Fig. 36, comprising a body portion p , firmly secured on the counter-shaft and provided with a spring-dog p' , normally held inward by its spring, the spring-dog being caused by the inward movement of a pivotally-supported lever u^2 (like the lever u on the opposite side of the machine) to press at the proper time against the spring-dog and force it from between the spokes of the wheel F, the normal tendency of the dog being to engage with the wheel, and thus cause the counter-shaft E to revolve with it. The levers u and u^2 are connected across the top of the machine, as shown in Fig. 3, by links u^3 and u^4 , pivoted at their adjacent extremities to opposite ends of a lever u^5 , pivoted at its center to a bracket u^6 , extending horizontally from the top of the frame A. It will thus be seen that when the rack B is actuated to throw the crank-finger, with the result already described, the outward movement produced of the yieldingly-held end of the arm or lever u moves the lever u^2 outward at the same time and effects release of the spring-dog of the clutch F' , and that when the two levers u and u^2 move inward (being controlled to do so by means hereinafter described) the spring-dog p' is forced from between the spokes of the wheel F.

Below and somewhat forward of the shaft E is a rotary shaft E' , journaled in the frame and carrying near one end, inside the left-hand side of the said frame, a pinion E^2 , Fig. 2, and outside the frame a cog-wheel E^3 , Fig. 1, indirectly meshing with the similar cog-wheel F through the medium of idle intermeshing gears o and o' , and between the wheel E^3 and frame on the shaft E' is a belt-pulley o^2 , connected by a crossed belt o^3 with a pulley o^4 on the driving-shaft o^5 .

G is the feed device, performing its function as hereinafter explained, and comprising a drum journaled at opposite ends in the frame of the machine to extend parallel with the drum C, and carrying loosely on one of its journals (that at the left-hand side of the machine, as shown in Fig. 2) a segmental rack G' , supporting on its upper edge a dog n , engaging with a ratchet n' , rigidly secured to the said journal, and the segmental rack G' is provided on its outer side with a short curved rack n^2 . The head of the drum G, to which the rack G' is adjacent, is provided at intervals around it near its periphery, the extent of which intervals is arranged according to the portion of its revolution the drum G is to be turned by the rack G' , as hereinafter explained, with stops m , Figs. 1, 2, and 5, into the path of which normally extends a vertical brake-arm m' , hinged near its base to swing laterally, being yieldingly confined in its normal position by a spring m^2 , and a link m^3 extends horizontally from the arm m' , with which it is connected, as shown in Fig. 5, beyond the frame A, where it engages with the crank-finger l' on a rod l , journaled in suitable bearings on the left-hand side of the

frame and extending beyond the forward end of the latter, there terminating in a crank-finger l^2 , extending against the lower portion of a pivotally-hung arm l^3 , Fig. 4, yieldingly held by a spring l^4 , and projecting at its lower end downward across the path of the horizontally-reciprocating rack B. The arm l^3 has secured to the inner side near its lower end a hook k , normally engaging a crank k' , Figs. 4 and 6, on the outer end of a rod k^2 , journaled in suitable bearings on the inner side of the frame A; and extending back nearly to the shaft E', where it has swiveled to its extremity a fork k^3 , embracing the shaft E' in a circular recess k^4 , formed around the sliding spring-controlled half of a common clutch I, both halves of which are supported on the said shaft at the inner side of the loose pinion E², to which one-half of the clutch is secured. The rotatory rod k^2 also carries a pinion k^5 in the path of the short curved rack n^2 on the segmental rack G', and also a notched cam k^6 , into which normally projects a lug k^7 on a stationary bar k^8 .

From the foregoing description it will be clear that with the pulley o^2 , Fig. 1, continuously rotating in the direction indicated by the arrow, and turning with it the shaft E', when the reciprocating rack B is moved in its guide in the direction toward the arm l^3 it strikes the latter, forcing it outward against the crank-finger l^2 , thereby turning the rod l in its bearings and the finger l' , which pulls the brake m' away from the stop m on the feed-drum G, engaging it, and permits the drum to be partially rotated, which is effected by the pulling of the hook k when the arm l^3 is forced outward, as described, and consequent turning of the crank k' , which turns the rod k^2 in a manner to cause it to produce engagement of the clutch I by the action of the cam k^6 against the stationary part k^7 , and consequent turning of the pinion E², the latter by its engagement with the segmental rack G' raising it, and through the medium of the dog n , acting on the ratchet n' , partly rotating the drum G. As the rack is raised in the manner described the pinion k^5 is engaged by the short curved rack n^2 , which turns the rod k^2 completely around till the crank k' again engages with the hook k , which will have been returned to its normal position by movement, toward the right-hand side of the machine, of the reciprocating rack B, (immediately after it has been moved in the opposite direction, as hereinafter explained,) which releases the arm l^3 , thereby obviously causing the brake m' to resume its normal position in the path of the stops on the drum G and separating the clutch I, which loosens the pinion E² and permits the segmental rack G' to fall by its own weight down to its normal position, ready to be again raised when engagement of the parts of the clutch I shall again be produced.

The inner journal of each pinion w , which, like the rack B, should incline, as shown, to-

ward the front end of the machine, is extended into a coiler K, comprising a rod i , projecting in the oblique direction of its pinion and provided at its inner extremity with an eccentric finger i' , and directly below the coilers is a tension device in the form of a drum L, having the journals at its opposite ends supported in vertically-elongated bearings i^2 , Fig. 1.

The wires M, to afford the horizontal wires of the fencing, (represented in Fig. 37,) or warp wires, are wound upon spools M', supported in desired number and at desired intervals on rollers j , journaled in the rear of the frame A, as shown in Figs. 1 and 2, or on any suitable support above the rear of the frame. From the spools M' the wires M, for stringing the machine initially, are wound, first from above, around the feed-drum G, and extended thence along the left sides (looking toward the front of the machine) and close to the coiling-rods i , around the tension-drum L to the take-up drum C, to the rear side of which they are secured by twisting their extremities into eyes and hooking them over hooks on a bar q^4 . On their way from the tension-drum L to the take-up C the warp-wires pass underneath a roller C', having a polygonal (octagonal) periphery, from along the margins of which extend series of pins i^3 , the series projecting alternately obliquely in opposite directions, respectively, toward opposite ends of the polygonal roller, which is journaled at its opposite extremities in corresponding ends of arms C², the opposite ends of which are pivotally supported at the sides of the base of the frame A, and the roller C' is yieldingly held down against the wires by its own weight and that of its pivotal supports and by springs C³.

On the feed-drum G the wires M are clamped to prevent them from slipping, and to clamp them we prefer to employ spring-clamps N, Fig. 15, suitably disposed around the drum. Each clamp N comprises a button h let into the periphery of the drum, and provided transversely, to extend lengthwise of the drum, with a sleeve h' , having a curved slot h^2 across its upper side, through which projects a bent finger h^3 on a spindle h^4 , extending longitudinally through the sleeve, in which it is adapted to oscillate, and provided on one end with a cam h^5 . The spindle is controlled by a spring h^6 on its opposite end, giving it a normal tendency to turn backward, whereby the curved slot in the sleeve guides the finger h^3 to slide the spindle toward the side of the button h , provided with a groove h^6 , through which the wire M is guided. This extends the cam end of the spindle across the groove to clamp the wire whenever the finger h^3 passes from underneath a concave stationary plate h^7 , one of which is provided for each series of clamps around the drum G, and is supported above the latter, (see Fig. 2,) and the plate h^7 serves, by turning the spindle forward through the

medium of the finger h^3 , when the drum turns, to withdraw the spindle and release the wire from the cam thereon. From the feed-drum the wires M pass, each between a tension-fork O, Fig. 34, secured in the path of the wire, the prongs of which diverge toward their extremities, so that wires of different thickness, and even knots formed by joints in the wires, may readily pass between them, and from the forks O, across the bases of the prongs of which a holding-roller O' for the wires M should be provided, the warp-wires pass to the tension-drum L over peripherally-grooved guide-pulleys O², supported on the frame A.

The operation of the machine constructed of the parts thus far described in detail, and strung with the warp-wires in the manner stated, is as follows: The winch w' is turned to the right and moves the rack B in the same direction, rotating the pinions w, and with them the coilers K, which wind the wires M sinuously around them. When the wires have been thus sinuously bent and the winch w' released, the rack B is prevented from being moved in the opposite direction under the strain of the coils around the rods i by a stop P, Figs. 3, 4, and 10, comprising a roller g, journaled to extend across the guideway of the rack B and recessed in one side, so that when that side is presented downward the rack can pass underneath it, but which normally presents its rounded surface to the path of the rack, and from which it is turned from a lever g', fulcrumed to the upper side of the front of the frame A, Fig. 4, being supported within easy reach of the operator, and having one end linked to a crank g² on the roller g, and a handle g³ at the opposite end. The effect of moving the rack B to the right in coiling the wires is also to actuate, through the toggle-lever mechanism v⁴ v⁵, &c., Figs. 11 and 13, the rods u³ u⁴, Fig. 3, to produce clutching of the wheel F, all as hereinbefore described; but the purpose of the last-named operation will be best understood by explanation thereof in another or further connection. It is immediately after the wires M have been coiled, as shown in Fig. 3, that a cross or woof-wire Q is fastened by the winding and stringing device R, the details of which are illustrated in Figs. 16 to 29, inclusive, and the particular construction and operation of which will be hereinafter explained. After a woof-wire Q has been adjusted (near the fingers i' of the coilers and ends of the coils) the length of finished fencing bounded by the woof-wire last applied has to be taken up. This is accomplished as follows: The handle g³, Fig. 4, is pulled down, thereby turning the roller g to permit the rack B to pass it, when the winch w' is turned backward to free the coilers K from the coils, which slackens the wires M by reducing the extent of their sinuous curves, and consequently permits the tension-drum L, which is supported normally by the warp-wires, to drop in its

elongated bearings i², Fig. 1, and take up the slack. The movement back, or toward the left of the rack B, causes it to turn the rod l, Fig. 1, and in the manner described effect the release from the feed-drum of its brake m' and the raising of the segmental rack G' by producing clutching of the shaft E', which causes the pinion E² to engage the teeth of the said segmental rack and raise it, thus forcing the dog n against the ratchet n' on the drum G and turning the latter around the extent of the arc of movement of the rack G', which is of predetermined length, and thus permits a given length to be paid off from the drum G with each operation. The take-up drum, which is held against the tendency of the segmental racks D and D' to turn it forward on its axis alone by the tension on the wires M, is freed by the paying off, and thereby permits the racks D and D' to fall forward through the arc of a circle, carrying with them, through the medium of the dogs z², the drum C, which thus takes up what is paid off from the feed-drum G. When the lowest tooth of the segmental rack G' has been raised to the pinion E², the curved rack n² will have turned the pinion k⁵, rod k², and cam k⁶ completely around, producing, in the manner described, disengagement of the clutch I and permitting the rack G' to fall down by its own weight to its normal position. The next operation is to again actuate the coilers K, which also produces movement of the rack B against the crank-finger v and turning it outward, whereby it effects straightening of the toggle-joint, and through the result and action of the arm u on the arm u², engagement of the clutch F' with the cog-wheel F, whereby the pinions D² are turned in the direction of rotation (forward) of the wheel F, and since they are always engaged by the racks D and D' raise the latter again. The same operation which produced straightening of the toggle-joint mechanism also, as will be remembered, threw the trip-finger r² forward to the dotted position x³, Fig. 11, while the racks D and D' were in the position to which they have fallen, so that when in the rise of the rack D' its stud z' impinged against the trip-finger it produced through turning of the crank-finger r' and raising of the forward end of the lever s, breaking of the toggle-joint, which thus permitted the spring u' to act upon the arm u in a direction to effect drawing of the arm u² against the spring-dog of the clutch F', and thus produce release from the wheel F of the clutch, and consequent standstill of the racks D and D' on reaching their highest positions. When the wires M have been again coiled, as stated, another woof-wire Q is fastened across the warp-wires, just in advance of the coilers, and the operations of uncoiling and actuating the feed and take-up are repeated. Of course as the take-up drum C increases in diameter owing to the accumulation upon it, the racks D and D' must fall less and less

far with each extra layer taken up, and we deem it desirable to assist their fall by means of an adequately stiff spiral spring D^3 , Fig. 2, fastened at one extremity to the forward 5 end of the frame A, and connected from its opposite extremity by a band D^4 with the shaft E, whereby when the latter is rotated by the rise of the racks the spring is distended by the winding of the bend.

10 The mechanism for winding and stringing the woof-wires across the wires M operates independently of the warp-wire's coiling, tension, feed, and take-up mechanisms, in the sense that it is actuated when they are at 15 rest and is capable of use for its purpose in attaching the woof-wires to warp-wires, however the latter may be sustained, as if tied at opposite ends to extend between stationary supports and without being coiled, or strung 20 from the spools M' over a drum, as the drum L, to a take-up C, and in the same way the said tension, feed, and take-up mechanisms could be employed to operate as or substantially in the manner described without the woof-wire 25 winding and stringing device, since it were of course possible, however impracticable, to apply the woof-wires by other means, as by hand.

Before describing in detail the woof-wire 30 winding and stringing mechanism it will assist in understanding it to state first in general terms its construction and manner of operation.

The device R is supported on a rotary 35 shaft R' , carrying a belt-wheel o^7 , Fig. 1, driven from a belt-wheel o^6 on the driving-shaft o^5 . The said device is constructed on the principle of the human jaw, with the lower portion adapted to rise and fall on a pivot 40 afforded by the shaft R' , and it extends from the shaft R' forward and obliquely downward nearly to the line of the extremities of the coilers, clamping between its upper jaw and the lower, when raised at the right time 45 by suitable cam mechanism, and endless belt R^2 , Fig. 26, caused to travel automatically toward the left-hand side of the machine during the woof-wire winding and stringing operation and to reverse and return the device 50 R to its starting-point at the opposite side of the machine immediately upon completion of the adjustment of a woof-wire. At the forward end of the woof-wire winding and stringing device is a hollow needle S, Fig. 28, of 55 approximately cylindrical shape and open along one side, having formed or provided around it near its center a pinion S' , divided by a circumferential central groove S^2 , and so supported in its bearings as to permit to it a 60 rotary and also a slight longitudinal reciprocating motion, and the forward end of the needle is threaded with the woof-wire just about long enough to reach across the warp-wires when wound around each, and which 65 we prefer to provide in the form of a coil S^5 , Fig. 29.

The operation of the needle when first set

in motion is first to fall upon (by the falling of the lower jaw) and surround the first wire M at the right hand side of the machine, and then to rotate about and reciprocate longitudinally along that wire, thereby winding around it the woof-wire into the form of knot illustrated in Fig. 30^c. The lower jaw is then caused by the cam mechanism to rise 70 and clamp the traveling endless belt R^2 , which moves it toward the left to the adjacent warp-wire and along the track, (shown in Figs. 31 to 33, inclusive,) slotted at intervals corresponding with the warp-wires, the device carrying with it a slotted bar held at one end by a spring, which retracts it when released, and the slots in which normally alternate with those in the track, whereby the lower jaw cannot fall into a slot in the track till one in the 80 spring-bar coincides with it. The arrangement is such that when the lower jaw has dropped the needle is actuated, and that when the needle has finished its work upon a wire M the jaw rises, clamping the traveling belt 90 and causing the device to be moved to the next warp-wire. When the end of the series of warp-wires is reached, the device R strikes a lever which throws a clutch to effect reversal of the direction of motion of the belt 95 R^2 , which then carries the device R back to its initial position.

Following is a description in detail of the woof-wire winding and stringing mechanism.

T is the lower jaw and T' the upper jaw. 100 We form the lower jaw of two flat bars f , each having a collar provided at one end, at which it loosely surrounds the shaft R' , and the bars converge toward their opposite ends, where they are rigidly connected on their upper 105 sides by a plate f' , fastened to the bars, and having a rectangular slot f^2 , Fig. 27, formed through it. To the under side of the bars f , below the slotted plate f' and on opposite sides of its slot, are secured bearings f^3 and 110 f^4 for the needle S, which carries the circumferentially-grooved pinion S' , hereinbefore referred to, (and which is slotted like the needle,) between its bearings. A rotary shaft f^5 is journaled toward one end in the bearings f^3 and f^4 above the needle, and toward 115 its opposite end in a bearing f^6 on a plate f^7 , extending across the bars f , near the shaft R' . The shaft f^5 carries, coincident with the slot f^2 in the plate f' , a pinion S^3 , Fig. 27, of peculiar construction, inasmuch 120 as it involves, besides cogs like those, but one short of the number around the slotted pinion S' on the slotted hollow needle S, a large laterally-conical tooth S^4 , and the shaft f^5 carries at its opposite or rear end a beveled pinion U' in mesh with and at a right angle with a beveled gear-wheel U, the hub of which loosely surrounds the hub of an arm V, hereinafter described, and is confined 125 against lateral play. The side of the wheel U opposite that on which its cogs are provided has formed or otherwise provided around its center a cam-groove U^2 , Fig. 16, of 130

especial shape, for the purpose of reciprocating the needle S to form the knot shown in Fig. 30, as hereinafter definitely explained, the reciprocation being produced in the rotation of the wheel (produced as hereinafter described) through the medium of a friction-roller f^8 , Fig. 16, extending into the cam-groove from the end of a rod f^9 bent, as shown, to adapt to it other parts it has to 5 pass in extending from the cam-groove along the bottom of a bar f of the lower jaw T to a side of the needle S, where a yoke f^{10} extends laterally from it between the bearings f^3 and f^4 and embraces the circumferential groove S^2 on the pinion S', the movements of the 10 yoke being guided by a guide-bar f^{12} , Fig. 28, crossing its stem and supported at opposite ends in adjacent sides of the bearings f^3 and f^4 .
 15 20 V (shown most clearly in Figs. 21 and 22) is an arm in the form of a flat bar, having a central opening and hub V^2 , at which it fits loosely over the shaft R' , to which it is keyed and on which it is confined against independent lateral movement adjacent to the wheel U, between collars V^3 and V^4 , and the arm V is provided near each of its extremities with a transverse pin e , extending beyond the sides of the arm and provided on each end with a 25 friction-roller e' . On the hub of the wheel U, next to the arm V, is a lug e^2 , Fig. 18, to which, between it and the adjacent side of the wheel, is pivoted a double-headed spring-dog d , one head of which is normally held by the spring 30 against a rigid stop e^3 on the side of the wheel U, while the other head normally extends into the path of the rollers e' on the adjacent side of the arm V. On the hub V^2 at the opposite side of the arm V, and thus between it and the hub of the wheel U, is a lug e^4 , like the lug e^2 on the hub. Beyond the lug e^4 on the said hub, which is loose on the shaft R' , is a cam V' , Fig. 21, between the base of which and the lug e^4 is pivoted a double-headed spring-dog d' , like the dog d , with one head 35 normally in the path of the friction-rollers e' on the left-hand side (regarded from the front of the machine) of the arm V; and the cam has a lug e^5 , Figs. 17 and 21, on its outer edge 40 near its base.
 45 50 The upper jaw T' comprises two parallel side bars c , secured at their rear ends to the collars V^2 and V^3 , which surround the shaft R' , and joined at their forward extremities by a cross-bar, whence depends a guide-bracket c' , at which the forward end of the device R is supported on a guide-rail c^2 , extending across the front end of the machine, adjacent to the coilers K, being supported at 55 opposite ends in the frame A. Behind the bracket c' is a plate c^3 , pivotally supported at its lower end on the bars f of the lower jaw T, and extending thence obliquely upward between the side bars c of the upper jaw T', as shown in Figs. 16 and 17. A lifting-bar 60 65 W is pivoted at one end between the side bars c , and extends thence backward through

a yoke W' , fastened at opposite ends to the side bars f of the movable jaw T and extending transversely over the upper jaw, where it 70 carries a forward-projecting belt-guard c^4 . The lifting-bar is notched, as shown at c^5 , Fig. 17, toward its free rear end where it extends upon the cam V' , the notch engaging the lug e^5 when the latter is brought coincident with it. 75

From the front side of the plate c^3 , near its upper end, projects a pin c^6 , Figs. 16 and 27, which we term the "finder," and which serves a purpose hereinafter described, and below the "finder-pin" c^6 is pivoted on the face of c^3 a spring-catch c^7 , having a finger c^8 projecting forward from its lower end, the pivot supporting the catch extending through a laterally-elongated opening c^9 therein, Fig. 27, and the spring which controls it tending 85 normally to pull it to bring the right-hand end of the slot c^9 against the pivot-pin.

X, Fig. 25, is an approximately U-shaped bearing rigidly supported upon the side bars c of the upper jaw T', near their rear end 90 thereof, with its open sides transversely of the bars c , and having horizontal lateral extensions 1 and 2 on two of its diagonally-opposite upper corners. A bar b , Figs. 19 and 35, constituting a stop and controlled by a 95 spring, as clearly shown in Fig. 19, is pivoted toward one end to a side of the bearing X, with its adjacent extremity passing under and beyond the extension 2 and formed into a hook, and its opposite extremity extending, 100 as shown in Fig. 35, normally into the path of the spring-dog d , and a companion bar b' , also controlled by a spring, as shown, is pivoted at one end to the opposite side of the same bearing and extends normally into the 105 path of the spring-dog d' , being removed from such path at intervals in the manner and for the purpose hereinafter described, by a cam b^3 (shown clearly in Fig. 24) below it on a rock-shaft b^4 , passing through an opening formed through a side of the bearing X, and controlled by a spring 4 to cause the cam b^3 normally to permit the stop b' to assume its 110 lowest position toward its free end. A finger b^5 extends transversely from the shaft b^4 near 115 the end provided with the spring 4 into the path of a stud b^6 , Fig. 16, on the outer or cam side of the gear-wheel U; and b^7 is a bent spring-brake pivoted at one end to a side bar c of the upper jaw T', and extending with its 120 opposite end into the path of the stud b^6 , being controlled by a suitable spring b^8 . A bar a , bent as shown and formed into a hook at its upper end, is pivoted at its lower end to a bracket a' on a cross-bar a^2 , bolted to the side 125 bars f of the movable or lower jaw T near the pinion U', its hooked end (which is normally under the control of a spring a^3) engaging with the hooked end of the stop b , which projects, as aforesaid, beyond the side 130 of the bearing X, having the extension 2; and the hooked arm a is confined laterally toward its upper end in a slot a^5 , Fig. 23, formed in the edge of a plate a^6 , secured to the base of

the bearing X, a slotted plate a^7 being adjustably secured to the plate a^6 by a set-screw a^8 passed through its slot, the plate having a beveled edge a^9 presented to the hooked pivotal bent bar a , whereby the latter, on adjusting the plate a^6 , to wedge it more or less between the edge of the hooked bar a and rear side of the bearing X shall, for a purpose hereinafter described, be adjusted with its hooked end farther from or nearer to the hook b^2 on the end of the stop b . A clamp Y is provided between the upper and lower jaws of the device R, and comprises a concave block 5, secured to the side bars f of the lower jaw T, and a concave block or strap 6, (see Fig. 26,) secured to coincide with the block 5 on the side bars c of the upper jaw. The endless belt R², Figs. 3 and 26, which serves to carry the device R, as hereinafter explained, back and forth across the warp-wires M, is supported at one end on a large pulley 7, journaled in suitable bearings on the right-hand side of the frame A above the plane of the guide-pulleys o², and passes at its opposite end, as clearly shown in Fig. 26, around three small pulleys 8, 9, and 10, supported on a suitable stationary bracket 12 on the frame A. The pulley 9 has an elongated shaft 13, carrying at its extremity a miter-gear 14, extending between two similar gears 15 and 16, fastened, with their cog-faces opposing each other, to the shaft R', each miter-gear 15 and 16 having on its inner face clutch-teeth, and a clutch-collar 17 surrounds the shaft R' between the gears 15 and 16, and is adapted to be thrown in and out of clutch with the teeth on either by ordinary means for the purpose in the form of a yoke on the end of a pivotally-supported arm 18. The arm 18, which is extended laterally by branch arms, as shown, is connected by a lengthwise shifting rod 19 with a pivotal arm 20 on the opposite or right-hand side of the machine, both pivotal arms extending with their free ends across the opposite sides or into the path of the device R, whereby, when the latter reaches the extremity of its play at the left-hand side of the machine, it will strike the parallel branch arm of the arm 18 and thereby throw the clutch-collar 17 into mesh with the teeth on the miter-gear 16. This will, owing to the continual revolution of the shaft R' in the direction indicated by the arrow on its driving-pulley R⁴, which is suitably geared to the belt-pulley on the driving-shaft o⁵, Fig. 1, turn the shaft 13 and pulley 9 in a direction to cause the lower part of the endless belt R², and which passes through the clamp Y, to travel toward the right-hand side of the machine, carrying with it the device R, which, when it reaches that side of the machine, strikes the arm 20, unclutching the described clutch mechanism and thereby bring itself, by producing stoppage of the traveling belt R², to a standstill at the location of its initial operation. The guide-rail c² is thickened transversely, Figs. 16, 17, and 33, by another rail

c¹⁰, secured to extend along its rear side, the rail c¹⁰ being lower at its upper edge than that of the rail c², affording an offset or recess above it, and serving to space from the guide-rail a track-rail Z in the form of a plate fastened to extend along the inner side of the rail c¹⁰, and provided in its upper edge at desired intervals apart with recesses 21, coinciding so closely with the warp-wires M that when the finder-pin c⁶ on the device R reaches one it may drop into it and cause the needle S (its longitudinal slot being then lowermost) to envelop the warp-wires, all as hereinafter described. Behind the rail Z is a rail Z', provided at intervals on its upper edge with recesses 22, (like the recesses 21 in the rail Z,) and secured to the rear side of the rail Z by pins 23 passing through longitudinal slots 24. Below each recess 22 is secured rigidly to the rail Z' a lug 25, which extends into the path of the finger c⁸, projecting forward from the spring-clutch c⁷ on the front end of the device R. The slotted rail Z' is held yieldingly at one end (the right-hand side of the machine regarded from the front thereof, represented at the right side of Fig. 3) by a spring 26, Fig. 31, connected at one end with the frame A and at its opposite end with an arm 27, rigidly fastened to the said rail Z', and serving, normally, to hold the slots 22 in the latter out of coincidence with the slots 21 in the rail Z. To operate the device R from its initial position at the right-hand side of the machine, and after the warp-wires have been strung in the manner already described, the needle S is first threaded. This is done by passing through its eye 28, Figs. 28 and 29, one end of the woof-wire Q, which we prefer to provide in the form of a coil S⁵, containing a length of the wire just about sufficient to extend across the warp-wires when wound about each. For convenience we provide a number of eyes 28 for the needle in a bar 29, dovetailed longitudinally and adjustably secured in the inner upper side of the needle, whereby as one eye wears out with use the bar 29 can be filed down and extended from the end of the needle to present another eye for use. When the free end of the coil S⁵ has been passed through the eye of the needle, all is ready for the winding and stringing of the woof-wire, which operation is started by manipulating a lever 30, Fig. 3, connected with the longitudinally-shifting rod 19 and readily accessible to the operator by suitable connections, as indicated, from the front of the machine, and which effects shifting of the rod 19 toward the right, whereby the clutch-collar 17 is caused to engage with the teeth on the beveled gear 15, thus producing rotation of the shaft 13 in a direction to carry the under part of the belt R² toward the left-hand side of the machine. At the start the parts of the device R are so disposed that the cam V' has raised the lever W, which, by striking against the top of the yoke W', has raised the lower jaw T, thereby causing the belt R² to be held in the clamp

Y. As the belt carries the device along the track c^2 the finger c^8 on the spring-catch c^7 engages yieldingly with a lug 25 on the spring-track Z' , but with sufficient positiveness to 5 carry the spring-track with it against the resistance of the spring 26 and produce coincidence of the recesses 22 in the latter with the recesses 21 in the stationary track Z , transversely across and upon which the track Z' the finder-pin c^6 projects. When the coincidence of the recesses has been produced, the cam V' will have been turned past the lever W , thus freeing the lower jaw and allowing the finder-pin to drop into the first 10 pair of the coincident recesses 21 and 22 it meets, thereby separating the clamp Y and allowing the belt R^2 to proceed without carrying the device R . As the finder-pin drops, the needle S , with its longitudinal slot lowermost, and which has been brought by the movement of the device R coincident with the first warp-wire M , drops by the release of the lower jaw T over the wire, when the needle-actuating mechanism, 15 until then stationary, comes into play. The dropping of the lower jaw causes the hooked end of the pivotal arm a to engage with that of the spring-stop b and raise the latter on its pivot toward its end in the path of the 20 spring-dog d out of such path. This action causes the pivotal double-ended spring of the dog d , owing to the normal tendency of such spring, to lower the end of the dog which was against the stop b below the latter, and consequently raise the other end into the path of 25 a roller e' on the arm V , which, as will be remembered, continually rotates with the shaft R' , and the roller e' engages with the end of the dog d , thus swung into its path and, 30 through the dog, turns the gear-wheel U forward. This, by the meshing of the wheel U with the pinion U' , rotates the shaft f^5 and pinion S^3 toward the right, (regarded from the front end of the machine,) and consequently 35 the pinion S' and needle S toward the left, around the first warp-wire M . When the needle first begins to turn on its axis around the said warp-wires M , (when the operator grasps with his pinchers the free end of the 40 coil S^5 on the opposite side of the eye from that through which it is threaded to hold it while the wire of the coil is being twisted,) the cam U^2 on the gear-wheel U moves the rod f^9 , and with it, through the medium of 45 the grooved pinion S' , the needle S backward, carrying the woof-wire Q of the coil, and while it is being twisted along the warp-wire to produce the elongated twist around the latter represented in Fig. 30^a, and in the continued rotation of the cam-wheel the cam, after allowing the reciprocating movement of the needle to rest at the extremity of its backward play long enough to wind the rear end of the knot to be formed straight around the 50 warp-wire, advances the rotating needle, thereby causing it to carry the strand of woof-wire back to the forward position and produce the

elongated forward twist represented in Fig. 30^b, at the rear extremity of which forward movement of the needle the cam U^2 allows it 70 to remain sufficiently long to wind the woof-wire once around the warp-wire and upon or over itself at or about the starting-point of the knot, producing the form of the latter represented in Fig. 30^c, which is desirable, 75 owing to its extreme security.

To produce the number of twists required to form the knot described, the pinion U' should be rotated three times by each rotation of the wheel U , and has therefore one-third the number of teeth of the latter. The cam-wheel U , to produce the formation of the knot or tie, makes a complete revolution, at the end of which the stud b^6 on its outer side, Fig. 16, comes against the finger b^5 , Fig. 24, 80 and through the latter turns the cam b^3 to lift the spring-stop b' away from the double-headed spring-dog d' , whereby the rear end of the latter is raised by the action of its spring into the path of a roller e' on the adjacent side of the rotating arm V , which, through the dog d' , effects raising of the loosely-supported eccentric V' , the lug e^5 on which is provided to engage with the notch in the lifting-bar W , to prevent accidental 85 falling of the loose eccentric while traveling. Raising of the eccentric V' lifts the lower jaw T , through raising the lifting-bar W , against the yoke and causes the blocks 5 and 6 to clamp the belt R between them and to 90 lift the finder-pin c^6 out of the two coinciding recesses in the tracks Z and Z' , whereby the latter is freed and retracted by the spring 26 to disturb the coincidence of its recesses with those of its companion track. 95 Of course the eccentric V' passes the lifting-bar W directly after lifting the jaw T ; but the disturbance of the coincidence of the recesses 21 and 22 affords a support on the rail Z' for the finder-pin until the coincidence 100 shall again be produced, which is accomplished in the manner already described by the clamping of the device R upon the belt R^2 . The distance or distances between the parallel warp-wires, whatever it or they may be, is 105 the same as between the recesses in the tracks Z and Z' . When, therefore, the belt has carried the device R to the next adjacent warp-wire and produced coincidence of the adjacent recesses 21 and 22, the finder-pin c^6 will 110 drop into the latter, and, by causing the described action of the hooked arm a on the hooked spring-stop b , again set the needle mechanism in motion; and, as should here be stated, as soon as the stud b^6 passes the 115 finger b^5 the latter is thrown back by the action of its spring 4, thereby permitting the spring-stop b' again to assume its normal position in the path of the dog d' , which, when with the completion of the revolution of the 120 shaft R' (one of which revolutions, as will thus be seen, is required for each of the two woof-wire winding and stringing operations) that dog comes against its stop,

it swings the dog on its pivot out of the path of the adjacent roller e' on the arm V. It is also to be noted in this connection that the stud b^6 , besides performing the function 5 described, serves, together with the spring b^7 , as a stop against backward rotation of the wheel U, and that the enlarged tooth S^4 on the pinion S^3 is adapted to mesh with the longitudinal slot in the needle.

- 10 The adjusting means shown in Fig. 23 for the hooked arm a serves to adjust the latter to cause it to engage sooner or later with the hook b^2 on the spring-stop b , according to requirement as to timing the production of the 15 needle's coincidence with a warp-wire with reference to the beginning of the rotary movement of the needle.

The foregoing operations of the device R in first winding the woof-wire from a coil S^5 20 upon one wire M, and then stringing it to the next, are repeated until the last of the warp-wires has had the woof-wire tied to it, when, on the raising of the lower jaw, the belt carries the device R against the lever system 18, 25 unclutching the clutch-collar from the clutch-teeth on the gear 15 and throwing it into clutch with those on the gear 16, whereby the direction of travel of the belt is reversed and the device R returned to its starting-point, 30 the finger on the spring-catch c' then passing under the lugs 25 in its path on the spring-track Z' , and the needle and lower-jaw actuating mechanisms obviously remaining inert during the return. When the device has 35 reached its initial position, it is brought to rest by the stoppage of the belt R^2 , produced by the striking of the device against the lever system 30, Fig. 3, which throws the belt-actuating mechanism out of clutch. When the 40 device R has finished the stringing of a woof-wire, and while it is returning to its position of initial operation, the operator turns the winch w' , thereby effecting movement toward the left-hand side of the machine of the rack 45 B and release of the wires M from the coilers K, whereby the tension-drum L drops in its slotted bearings i^2 and maintains the tension of the warp-wires, which obviously become somewhat distended at the coils when the latter are released from the coilers. The aforesaid movement of the rack B produces (after the release of the brake M', as already explained) the setting in motion, in the manner hereinbefore described, of the feed-drum 50 G, which is turned forward a part (as one-eighth) of its revolution, feeding that extent to the coilers from the spools M' and paying off the same extent to the take-up drum C, which extent is wound upon the take-up by 55 the falling forward of the segmental racks D and D', and which are subsequently raised in the manner described while the operator is producing another coil in each warp-wire, and thereby also producing movement of the 60 rack B toward the right-hand side of the machine to effect straightening of the toggle-lever mechanism on that side of the machine,

with the attendant results, all hereinbefore explained. When a desired length of the finished product of the machine has been taken up by the drum C, which length may be determined, among other ways, by keeping track of the number of woof-wire coils S^5 used, the latter being applied at predetermined distances apart, the warp-wires are 75 severed near the take-up (and formed at their several ends into loops, for subsequent attachment to the drum C) and the severed end of the taken-up product secured to the roll. The take-up drum C is then removed from the 80 frame A by turning its screw-journal y in the direction to withdraw it and the head q , when the bars forming the drum are drawn out of the end of the roll, to be again readjusted for the continued operation of the machine as 85 soon as the drum they afford has been replaced and the several looped ends of the warp-wires hooked upon it.

The extremely complicated nature of the mechanism constituting our machine as illustrated and of the operations of the various parts has rendered necessary, we think, or, at least, advisable, the foregoing detailed description. We wish, however, to have it clearly understood that we do not consider 95 our invention to lie in mere details of the construction, many of which may be, as we and others skilled in the art to which our machine relates might readily suggest, altered and simplified, and some even entirely 100 omitted. The appended claims are, therefore, intended to be construed as broadly as the state of the art will permit for a machine involving, generally, any construction which, when broadly considered, is analogous to ours 105 for its purposes, first, with relation to the warp-wires alone, and this whether or not the latter are coiled; second, with relation to mechanism which will automatically wind and string the woof-wire across the warp-wires, and, third, with relation to the co-operation 110 of the warp and woof wire weaving mechanisms.

What we claim as new, and desire to secure by Letters Patent, is—

1. In a machine for use in the manufacture of wire fence comprising wires crossing each other and secured together where they cross, the combination, with a frame A, of a feed device G, to which the warp-wires are guided from the wire-supply and upon which they are passed to the take-up, the feed device being normally held against movement, clamps on the feed device for holding the warp-wires against slipping, and a take-up C, to which are secured the warp-wires leading from the device G, and turning with the movement of the feed device to wind upon it the finished fencing, substantially as described.

2. In a machine for use in the manufacture 130 of wire fence comprising wires crossing each other and secured together where they cross, the combination, with a frame A, of a feed device G, normally held against movement,

spools M, supported at their peripheries and free to be revolved on bearings and carrying the warp-wires M, guided thence to and upon the feed device, clamps on the feed device 5 for holding the warp-wires against slipping, and a take-up C, to which are secured the wires M, leading from the device G and turning with the movement of the feed device to wind upon it the finished fencing, substantially as described.

3. In a machine for use in the manufacture of wire fence comprising wires crossing each other and secured together where they cross, the combination, with a frame A, of a feed-drum G, normally held against movement and provided with spring-clamps N, each comprising a button h let into the drum and provided with the slotted sleeve h', a spindle h⁴, carrying a finger extending through the 20 slot, a cam h⁸ on one end of the spindle, and a spring h⁵, concave plates h⁷, spools M', supported to be revolved on bearings and carrying the warp-wires M, guided thence to the drum G, and held thereon by the clamps N, 25 and a take-up C, to which are secured the wires M, leading from the drum G and turning with the movement of the feed-drum to wind upon it the finished fencing, substantially as described.

30 4. In a machine for use in the manufacture of wire fence comprising sinuous wires crossed by other wires and secured together where they cross, the combination, with a frame A, of a tension device L, loosely supported in its bearings, a feed device G, on which the warp-wires M, guided on the tension device, are passed and which is normally held against movement, a take-up C, to which the warp-wires leading from the device G are secured 35 and turning with the movement of the feed device to wind upon it the finished fencing, and rotatory coilers K, supported near the front end of the machine, substantially as described.

45 5. In a machine for use in the manufacture of wire fence comprising wires crossing each other and secured together where they cross, the combination, with a frame A, of a feed device G, to which the warp-wires are guided 50 from the wire-supply and upon which they are clamped and passed to the take-up, the feed device being normally held against movement, and a take-up drum C, to which the warp-wires leading from the device G are secured and turning with the movement of the feed device to wind upon it the finished fencing, and comprising heads q and q', having 55 sockets q² on their opposing surfaces, supporting the opposite ends of bars q⁴, and one of 60 said heads having a threaded journal and bearing, whereby it may be adjusted with relation to the opposite head, substantially as described.

65 6. In a machine for use in the manufacture of wire fence comprising wires crossing each other and secured together where they cross, the combination, with a frame A, of a feed

device G, to which the warp-wires are guided from the wire-supply and upon which they are clamped and passed to the take-up, and 70 a rotatory take-up C, eccentrically weighted, having secured to it the warp-wires leading from the feed device, and actuated, with movement of the feed device, by the gravity of the eccentric weight to turn the take-up 75 and wind upon it the finished fencing, substantially as described.

7. In a machine for use in the manufacture of wire fence comprising sinuous wires crossed by other wires and secured together 80 where they cross, the combination, with a frame A, of a tension device L, loosely supported in its bearings, a feed device G, on which the warp-wires M, guided on the tension device, are passed and clamped and which 85 is normally held against movement, a take-up C, to which are secured the warp-wires leading from the device G and turning with the movement of the feed device to wind upon it the finished fencing, rotatory coilers K, supported near the front end of the machine, a 90 rack B, engaged and reciprocated by rotation of the coilers, and mechanism extending into the path of the rack and connected with the feed device and actuated by the rack to move 95 the said feed device, substantially as described.

8. In a machine for use in the manufacture of wire fence comprising sinuous wires crossed by other wires and secured together 100 where they cross, the combination, with a frame A, of a tension device L, loosely supported in its bearings, a feed-drum G, on which the warp-wires M, guided on the tension device, are passed and clamped and which is 105 normally held against movement, a segmental rack G', pivotally supported near and adapted to engage with the drum G, a rotary shaft E', carrying a pinion E² and a belt-pulley E³, geared to a driving-shaft o⁵, a clutch I on the 110 shaft E', a take-up C, to which are secured the warp-wires leading from the drum G and turning with rotation of the feed-drum to wind upon it the finished fencing, rotatory 115 coilers K, supported near the front end of the machine, a rack B, engaged and reciprocated by rotation of the coilers, and a clutch-actuating rod k², extending from the clutch I into the path of the rack, substantially as and for the purpose set forth.

9. In a machine for use in the manufacture of wire fence comprising sinuous wires crossed by other wires and secured together 120 where they cross, the combination, with a frame A, of a tension device L, loosely supported in its bearings, a feed-drum G, on which the warp-wires M, guided on the tension device, are passed and clamped, a segmental rack G', pivotally supported near and adapted to engage with the drum G and carrying a curved rack n², stops m on the feed-drum, a rotary shaft E', carrying a pinion E² and a belt-pulley E³, geared to a driving-shaft 125 o⁵, a clutch I on the shaft E', a spring-brake 130

m' , normally engaging with a stop m , and controlled for its release through a rod l , a take-up C , to which are secured the warp-wires leading from the drum G and turning with rotation of the feed-drum to wind upon it the finished fencing, rotatory coilers K , supported near the front end of the machine, a rack B , engaged and reciprocated by rotation of the coilers, and a rotatory clutch-actuating rod k^2 , having swiveled to one end a clutch-fork and carrying a pinion k^3 in the path of the rack n^2 and extending into the path of the rack B , substantially as described.

10. In a machine for use in the manufacture of wire fence comprising sinuous wires crossed by other wires and secured together where they cross, the combination, with a frame A , of a tension device L , loosely supported in its bearings, a feed-drum G , on which the warp-wires M , guided on the tension device, are passed and clamped, a segmental rack G' , pivotally supported near and adapted to engage with the drum G , stops m on the feed-drum, a rotary shaft E' , carrying a pinion E^2 and a belt-pulley E^3 , geared to a driving-shaft o^5 , a clutch I on the shaft E' , a spring-brake m' , normally engaging with a stop m and controlled for its release through a rod l , a take-up C , to which are secured the warp-wires leading from the drum G , a segmental rack D , pivotally supported near and engaging with the take-up drum C and operating to turn the latter with rotation of the feed-drum to wind upon it the finished fencing, rotatory coilers K , supported near the front end of the machine, a rack B , engaged and reciprocated by rotation of the coilers, a rotatory clutch-actuating rod k^2 , having swiveled to one end a clutch-fork and extending into the path of the rack B at one side of the machine, a rotatory shaft E , supported above the take-up and carrying a pinion D^2 in the path of the rack D and loosely at one end a cog-wheel F , geared to a similar wheel on the shaft E' , and a clutch F' on the shaft E near the wheel F , and controlled in one direction by the rack B through mechanism extending into the path of the said rack at the opposite side of the machine and in the contrary direction from the rack D , substantially as described.

11. In a machine for use in the manufacture of wire fence comprising wires crossing each other and secured together where they cross, the combination, with a frame A , of a feed device G , to which the warp-wires are guided from the wire-supply and upon which they are passed to the take-up, tension-forks O , rigidly secured to the frame in the paths of the warp-wires to the said feed device, which is normally held against movement, and a take-up C , to which are secured the warp-wires leading from the device G and turning with the movement of the feed device to wind upon it the finished fencing, substantially as described.

12. In a device for use in the manufacture

of wire fence comprising wires crossing each other and secured together where they cross, for winding and stringing a woof-wire upon the warp-wires, a longitudinally-slotted needle S , adapted to hold the woof-wire and supported to rotate in its bearing, substantially as and for the purpose set forth.

13. In a device for use in the manufacture of wire fence comprising wires crossing each other and secured together where they cross, for winding and stringing a woof-wire upon the warp-wires, a longitudinally-slotted needle S , having adjustably secured to it a bar 29, provided with eyes 28, through which to thread the needle with the woof-wire, the said needle being supported to rotate in its bearing, substantially as and for the purpose set forth.

14. In a device for use in the manufacture of wire fence comprising wires crossing each other and secured together where they cross, for winding and stringing a woof-wire upon the warp-wires, a longitudinally-slotted needle S , adapted to hold the woof-wire and supported to be rotated on its own axis and be reciprocated longitudinally in its bearing, substantially as and for the purpose set forth.

15. In a device for use in the manufacture of wire fence comprising wires crossing each other and secured together where they cross, for winding and stringing a woof-wire upon the warp-wires, the combination of a rotary shaft R' , supported in suitable bearings and carrying a beveled cog-wheel U , having a cam U^2 on one side, a longitudinally-slotted needle S , supported to be rotated and reciprocated in its bearing, which is pivotally supported from the shaft R' and provided with a pinion S' , a pinion S^3 , supported on one end of a rotary shaft f^5 to mesh with the pinion S' , a beveled pinion U' at the opposite end of the shaft f^5 , in mesh with the wheel U , and a reciprocating rod f^9 , supported to engage at one end with the needle and at its opposite end with the cam, substantially as and for the purpose set forth.

16. In a device for use in the manufacture of wire fence comprising wires crossing each other and secured together where they cross, for winding and stringing a woof-wire upon the warp-wires, the combination of a rotary shaft R' , supported in suitable bearings and carrying a beveled cog-wheel U , having a cam U^2 on one side, a longitudinally-slotted needle S , supported to be rotated and reciprocated in its bearing, which is pivotally supported from the shaft R' and provided with a circumferentially-grooved pinion S' , a pinion S^3 , having an enlarged cog S^4 and supported on one end of a rotary shaft f^5 , to mesh with the pinion S' , a beveled pinion U' at the opposite end of the shaft f^5 , in mesh with the wheel U , and a reciprocating rod f^9 , supported to engage at one end with the groove in the pinion S' and at its opposite end with the cam, substantially as and for the purpose set forth.

17. In a machine for the manufacture of wire fence comprising wires crossed by other wires and secured together where they cross, the combination, with a frame A, on which are strung the warp-wires M, of woof-wire winding and stringing mechanism comprising an endless traveling belt R², supported to extend across the frame and reversible as to direction of its motion, and a device R, comprising a rotary shaft R', journaled in the frame A and having hinged to it a lower jaw T, an upper jaw T', supported at one end on the shaft R' and at its opposite end on a track c² near the front end of the machine, a finder-pin c⁶ on the upper jaw, a recessed track Z, and a movable spring-controlled recessed track Z' behind the track c², a longitudinally-slotted needle S on the lower jaw and adapted to rotate in its bearing and actuated from the shaft R', an eccentric V' on the said shaft to engage through intermediate mechanism with the hinged jaw T and actuated alternately with the needle-actuating mechanism to raise the said lower jaw and clamp the belt R², and a catch c⁷ on the jaw T', to engage the track Z', the whole being constructed and arranged to operate substantially as and for the purpose set forth.
18. In a machine for the manufacture of wire fence comprising wires crossed by other wires and secured together where they cross, the combination, with a frame A, on which are strung the warp-wires M, of woof-wire winding and stringing mechanism comprising an endless traveling belt R², supported to extend across the frame and reversible as to direction of its motion, and a device R, comprising a rotary shaft R', journaled in the frame A and having hinged to it a lower jaw T, an upper jaw T', supported at one end on the shaft R' and at its opposite end on a track c² near the front end of the machine, a finder-pin c⁶ on the upper jaw, a stationary recessed track Z, and a movable spring-controlled recessed track Z' behind the track c², a longitudinally-slotted needle S on the lower jaw and adapted to rotate and reciprocate in its bearing and actuated from the shaft R', a yoke W', extending from the lower over the upper jaw, a lifting-bar W, pivotally supported at one end on the jaw T' and extending at its opposite end into the path of the eccentric V', a pivotal hooked bar a, extending from the lower jaw across the hooked end of the stop b, and means, substantially as described, for raising the stop b' out of the path of the spring-dog d', the whole being constructed and arranged to operate substantially as and for the purpose set forth.
19. In a machine for manufacturing wire fence comprising wires crossing each other and secured together where they cross, the combination, with a frame A, of a feed device G, to which the warp-wires are guided from the wire-supply and upon which they are passed to the take-up, the feed device being normally held against movement, a take-up C, to which are secured the warp-wires leading from the device G and turning with the movement of the feed device to wind upon it the finished fencing, and woof-wire winding and stringing mechanism comprising an endless traveling belt R², supported to extend across the frame A, means for controlling the movement of the belt and for reversing the direction of its movement controllable from opposite sides of the machine, and a device R, comprising a rotary shaft R', journaled in the frame and having hinged to it a lower jaw T, an upper jaw T', supported at one end on the shaft R' and at its opposite end on a track c² near the front end of the machine, a finder-pin c⁶ on the upper jaw, a recessed track Z, and a movable spring-controlled recessed track Z', a longitudinally-slotted needle S on the lower jaw and adapted to rotate in its bearing and actuated from the shaft R', means, substantially as described, actuated

from the said rotary shaft alternately with the needle-actuating mechanism, for raising the lower jaw and thereby clamping the belt R², and a catch c⁷ on the jaw T', to engage the track Z', the whole being constructed and arranged to operate substantially as and for the purpose set forth.

21. In a machine for manufacturing wire fence comprising sinuous wires crossed by other wires and secured together where they cross, the combination, with a frame A, of a tension device L, loosely supported in bearings, a feed device G, on which the warp-wires M, guided on the tension device, are passed, and which is normally held against movement, a take-up C, to which the warp-wires leading from the device G are secured and turning with the movement of the feed device to wind upon it the finished fencing, rotatory coilers K, supported near the front end of the machine, and woof-wire winding and stringing mechanism comprising an endless traveling belt R², supported to extend across the frame A, means for controlling the movement of the belt and for reversing the direction of

its movement controllable from opposite sides of the machine, and a device R, comprising a rotary shaft R', journaled in the frame and having hinged to it a lower jaw T, an upper jaw T', supported at one end on the shaft R', and at its opposite end on a track c² near the front end of the machine, a finder-pin c⁶ on the upper jaw, a recessed track Z, and a movable spring-controlled recessed track Z', a longitudinally-slotted needle S on the lower jaw and adapted to rotate and reciprocate in its bearing and actuated from the shaft R', means, substantially as described, actuated from the said rotary shaft alternately with the needle-actuating mechanism, for raising the lower jaw and thereby clamping the belt R², and a catch c⁷ on the jaw T', to engage the track Z', the whole being constructed and arranged to operate substantially as and for the purpose set forth.
